CABINET FOR ELECTRONIC ALARM SYSTEM

Dale Lincoln, Lafayette, Calif., assignor to Systron-
Donner Corporation, Concord, Calif.

Filed June 28, 1971, Ser. No. 157,819

Term of patent 14 years

Int. Cl. D29—99; D13—99

U.S. Cl. D72—1

FIG. 3

FIG. 2

FIG. 1

FIG. 4

FIG. 5

FIG. 6

FIG. 1 is an isometric view of a cabinet for electronic alarm system incorporating my new design;

FIG. 2 is a rear elevational view of the cabinet for electronic alarm system, as viewed in FIG. 1;

FIG. 3 is an elevational view of the left end of the cabinet for electronic alarm system, as viewed in FIG. 2;

FIG. 4 is a top plan view of the cabinet for electronic alarm system, as viewed in FIG. 1;

FIG. 5 is a front elevational view of the cabinet for electronic alarm system, as viewed in FIG. 1; and

FIG. 6 is a bottom plan view of the cabinet for electronic alarm system, as viewed in FIG. 1.

Both ends of the cabinet for electronic alarm system are identical.

I claim:

The ornamental design for a cabinet for electronic alarm system, as shown and described.
